(57) **CLAIM**

The ornamental design for a rabbit ears vibrator, as shown and described.

DESCRIPTION

FIG. 1 is a perspective view of a rabbit ears vibrator with the ornamental design;

FIG. 2 is a front elevation view of the rabbit ears vibrator of FIG. 1;

FIG. 3 is a rear elevation view of the rabbit ears vibrator of FIG. 1;

FIG. 4 is a side elevation view of the rabbit ears vibrator of FIG. 1;

FIG. 5 is a top plan view of the rabbit ears vibrator of FIG. 1; and,

FIG. 6 is a bottom plan view of the rabbit ears vibrator of FIG. 1.

The broken lines shown in the drawings are for illustrative purposes only and form no part of the claimed design.
